(57) **CLAIM**

The ornamental design for a pill packaging, as shown and described.

DESCRIPTION

FIG. 1 is a front perspective view of a first embodiment of the pill packaging.

FIG. 2 is a front elevation view of the first embodiment.

FIG. 3 is a back elevation view of the first embodiment.

FIG. 4 is a right side elevation view of the first embodiment.

FIG. 5 is a left side elevation view of the first embodiment.

FIG. 6 is a top elevation view of the first embodiment.

FIG. 7 is a bottom elevation view of the first embodiment.

FIG. 8 is a front perspective view of a second embodiment of the pill packaging.

FIG. 9 is a front elevation view of the second embodiment.

FIG. 10 is a back elevation view of the second embodiment.

FIG. 11 is a right side elevation view of the second embodiment.

FIG. 12 is a left side elevation view of the second embodiment.

FIG. 13 is a top elevation view of the second embodiment; and,

FIG. 14 is a bottom elevation view of the second embodiment.

The broken line showing is for the purpose of illustrating environmental structure, and forms no part of the claimed design.

1 Claim, 10 Drawing Sheets
